FLANGE HINGE

Paul M. Stephens, Ashland, Mo.

Application June 12, 1939, Serial No. 278,599

15 Claims. (Cl. 16—135)

This invention relates to an improved construction of concealed hinge for swinging closures and is particularly designed and adapted for use on motor vehicle doors to provide a hinge which will be completely concealed when the door is in a closed position.

More particularly, it is an aim of this invention to provide an improved construction of hinge adapted to be disposed between a door frame pillar and the adjacent edge of a door to completely conceal the hinge from either side of the door, when the door is in a closed position.

Still another aim of the invention is to provide a hinge including spaced superposed hinge leaves for swingably mounting a door relatively to a door frame pillar and having means whereby the door will be moved outwardly of the door frame pillar as it is swung to an open position.

Still another object of the invention is to provide a hinge including a hinge leaf adapted to be fixedly mounted and a second hinge leaf adapted to be swingably mounted, said last mentioned leaf being of a novel shape and adapted to be secured to the hinged edge of a closure for moving the closure outwardly of the frame in which it is mounted, when it is swung to an open position.

Still another aim of the invention is to provide a pair of spaced superposed hinge leaves having hinge pins fixed thereto and swivelly connected to each other for swingably mounting the leaves relatively to one another.

Other objects and advantages of the invention will hereinafter become more fully apparent from the following description of the drawing, which illustrates a preferred embodiment thereof, and wherein—

Figure 1 is a horizontal sectional view of a portion of a conventional motor vehicle door and door frame shown connected by means of the improved hinge, which is shown partly in plan and partly in horizontal section.

Figure 2 is a vertical sectional view taken substantially along the plane of the line 2—2 of Figure 1.

Figure 3 is an enlarged side elevational view, partly in section, showing the hinge detached and showing in detail the means for swivelly connecting the hinge pins.

Figures 4 and 5 are horizontal sectional views taken substantially along the planes of the lines 4—4 and 5—5, respectively, of Figure 3.

Figure 6 is a plan view of the lower hinge leaf, and

Figure 7 is a similar view of the upper hinge leaf.

Referring more particularly to the drawing, wherein like reference characters designate like or corresponding parts throughout the different views, 10 designates generally a portion of a flanged door, of the type conventionally used on motor vehicles, and 11 designates generally a portion of the door frame including a portion of the frame pillar 12. The door and door frame pillar are provided with complementary overlying flanges 13 and 14 at their outer and inner edges, 10 respectively, as best seen in Figure 1. The pairs of flanges 13 and 14 overlap, as seen in dotted lines in Figure 1, when the door 10 is in a closed position to close the space between the hinged edge of the door and the pillar 12. These parts are of conventional motor vehicle construction and are illustrated and described merely to better illustrate the use and application of the hinge designated generally 15 and comprising the invention.

Hinge 15 includes a lower leaf 16 provided with a plurality of spaced openings 17 for receiving screw fastenings 18 to secure the hinge leaf 16 of the hinge 15 to the pillar 12. The leaf 16 has an enlarged end 19 provided with a bore 20 extending longitudinally therethrough, for a purpose which will hereinafter be described.

Hinge 15 also includes an upper leaf 21 including a rear side or wall 22, a front side or wall 23, spaced therefrom and disposed contiguously therewith, and an end portion 24 connecting sides 22 and 23. As best seen in Figure 7, the inner face of the side 22 curves inwardly or away from the side 23 as it approaches the end 24 so that the leaf 21, in the plan view, forms a gooseneck. The free end of the rear side 22 is enlarged to form the end 25, similar to end 19, which is provided with a bore 26, corresponding to the bore 20, which extends longitudinally therethrough. Portions 19 and 25 are each provided with a smaller bore 27 which extend transversely therethrough and which communicate with the longitudinal bores 20 and 26. The side 23 is provided with openings 28 to receive additional threaded fastenings 18, insertable therethrough from its inner face for engaging the edge of the door 10 to mount the door on the leaf 21 of the hinge 15. The rear side 22 is provided with enlarged openings 29 which align with the openings 28 for receiving a suitable tool, not shown, for applying or removing the last mentioned fastenings 18. Openings 11 and 28 are beveled, as best seen in Figures 6 and 7, respectively, so that the headed ends of the fastenings 18 may be countersunk therein.

A hinge pin or bolt 30 is provided with a shank 31 for removably engaging the bore 20 and which is snugly disposed therein. Shank 31 is provided with a transverse bore 32 to align with the bore 5 27 of the portion 19 to receive a rivet or other fastening 33 for keying the bolt 30 to the leaf 16. The lower, free end of the shank 31, which is disposed substantially flush with the lower edge of the portion 19, is provided with a threaded recess 10 to receive the threaded shank of a bolt 34 having an enlarged head for engaging the lower end of the portion 19. A bolt, designated generally 35, is provided with a corresponding shank 31 mounted in the bore 26 of the hinge leaf 21 and 15 secured thereto by a fastening 33 and a bolt 34 in the same manner as heretofore described in regard to the bolt 30.

The upper end of the bolt or pin 30 is provided with a head, designated generally 36, having an 20 enlarged lower portion 37 provided with a threaded periphery and a smaller upper portion 38 provided with a concave recess 39 in its upper face. The lower end of the bolt 35 is provided with a head 40 provided with a concave recess 25 41 in its lower face. The heads 36 and 40 are disposed adjacent each other and between the adjacent edges of the hinge leaves 16 and 21.

A socket nut 42 is provided with an opening 43 in its face for loosely engaging the shank 31 of the bolt or pin 35 adjacent the head 40 to thereby position the bolt 40 within the upper portion 30 of the socket 42. The lower end of the socket 42 is internally threaded to engage the threaded portion 37 of the head 36 to connect the bolts or pins 30 and 35 and the leaves 16 and 21. To prevent socket nut 42 from turning relatively to the bolt head 36 and becoming accidentally disengaged, the threaded periphery of the portion 37 is provided with a groove 44 disposed 35 laterally of its threads for receiving a set screw 45 mounted in the socket nut 42 to thereby key the socket nut to the bolt or pin 30.

Head 40 is loosely mounted in the socket nut 42 to rotatably mount it relatively to the bolt 45 30 so that the bolts or pins 30 and 35 are swivelly mounted relatively to each other. In order to prevent the weight of the hinge leaf 21 and the door 10 supported thereby from resting on the bolt or pin 39 or the socket nut 42 so as to cause 50 friction, a ball bearing 46 is mounted in the concave recesses 39 and 41 to provide anti-friction means and to space the bolt or pin heads 36 and 40 from each other. The opposite or upper face of the head 40 is provided with an annular groove 55 47, surrounding the shank 31 of the pin 35 while the socket 42, on its inner side and surrounding the opening 43 is provided with a similar annular groove, which grooves combine to form a raceway for a plurality of small ball bearings 48 which cooperate with the ball bearing 46 to form 60 anti-friction means to permit the bolt or pin head 40 to rotate freely in the socket 42.

From the foregoing it will be obvious, that the hinge 15 will permit the door 10 to swing freely 65 relatively to the frame 11 and due to the goose-neck shape of the hinge leaf 21 the door 10 will move outwardly of the frame 11 as it is swung to an open position so that the flange portion 13 of door 10 will move outwardly and away from 70 the complementary portions 13 of the pillar 12 so that the door 10 may be swung to a fully opened position, substantially at right angles to the door frame without the flange portions 13 contacting one another. When the door 10 is moved 75 to a closed position, the pairs of flanges 13 and

14 will close the space between the door and the pillar 12 to completely conceal the hinge 15 therein. Due to the fact that the hinge leaves 16 and 21 are disposed in superposed relationship relatively to each other, the width of this space may be made substantially less than would be possible if these hinged leaves were in abutting relationship when the door was in a closed position.

Various modifications and changes are contemplated and may obviously be resorted to as only a preferred embodiment of the invention has been illustrated and described.

I claim as my invention:

1. A closure hinge comprising a pair of superposed hinge leaves, bolts detachably connected to said leaves and keyed thereto, said bolts being provided with adjacently disposed heads, the head of the bolt of the lower leaf including an externally threaded portion, an internally threaded socket nut engaging said threaded portion, and disposed between the adjacent edges of said leaves, means for keying said socket nut to said threaded portion, the head of said other bolt being loosely disposed in said socket nut above the head of said first mentioned bolt, and said socket nut having an opening at the top in which the shank of said last mentioned bolt is loosely disposed for rotatably mounting the last mentioned bolt relatively to the first mentioned bolt to swingably mount the upper hinge leaf relatively to the lower hinge leaf.

2. A hinge as in claim 1, the adjacent faces of said bolt heads being provided with opposed concave recesses, and a ball bearing disposed in 34 said recesses for supporting the head of the upper bolt in spaced relationship to the head of the lower bolt.

3. A hinge as in claim 1, the adjacent faces of 40 said bolt heads being provided with opposed concave recesses, a ball bearing disposed in 41 said recesses for supporting the head of the upper bolt in spaced relationship to the head of the lower bolt, the opposite side of the head of the upper bolt being provided with an annular 45 groove, surrounding its shank, said socket being provided with an annular groove on its inner side surrounding the opening contained therein, and said annular grooves forming a raceway for a plurality of ball bearings.

4. A hinge as in claim 1, said upper leaf including spaced contiguous sides connected by an end portion, remotely disposed relatively to the supported end of the leaf, and said outer side being provided with openings for receiving fastenings 55 for securing it to a swinging closure.

5. A hinge as in claim 1, the upper leaf of said hinge being provided with spaced contiguous sides connected by an end portion and forming a gooseneck, the free end of one of the sides being provided with a bore to receive the shank of the last mentioned bolt, and said other side being apertured to receive fastenings for securing a swinging closure thereto.

6. In a hinge, a pair of bolts disposed in end 65 to end relationship, said bolts having heads adjacently positioned relatively to each other, a socket member detachably fixed to one of said heads and loosely enclosing the other head for swivelly mounting the last mentioned bolt relatively to the first mentioned bolt, and hinge flaps fixed to said bolts.

7. A hinge as in claim 6, the adjacent faces of 70 said bolt heads being provided with opposed arcuately shaped recesses, and a ball bearing 75

disposed in said recesses for spacing the bolt heads from each other.

8. A hinge as in claim 6, the hinge flap of the rotatably mounted bolt being of gooseneck shape and being provided with apertured outer portions for receiving fastenings for connecting said outer portions to a swinging closure.

9. A hinge as in claim 6, comprising threaded means on the interior of said socket for detachably engaging threads on the head of said first mentioned bolt, the threaded portion of said bolt being provided with a groove disposed transversely to the threads, and a set screw mounted in the socket for engaging said groove to detachably key the socket to said first mentioned bolt.

10. A hinge as in claim 6, one of said flaps comprising a flap plate adapted to be secured to the pillar of a door frame, said other flap comprising a gooseneck member, the outer portion of said gooseneck member being adapted to be secured to a swinging closure.

11. In a hinge for swinging closures, a hinge comprising a pair of superposed spaced hinge leaves adapted to be disposed between a closure and a closure frame pillar, one of said leaves being fixed to the pillar, said other leaf having an outwardly offset portion fixed to the closure for spacing it from the pillar, and means connected to said leaves, said means being swivelly connected to each other for swingably mounting the last mentioned leaf relatively to the first mentioned leaf, said means comprising bolts fixed to the hinge leaves, said bolts having heads disposed between the adjacent edges of said leaves,

and a socket member detachably connected to said heads for swivelly mounting the bolts relatively to each other.

12. In a hinge for vehicle doors, a pair of hinge leaves disposed in superposed spaced relationship relatively to each other and between a pillar of a door frame and the adjacent edge of a door, one of said leaves being secured to said pillar, the other leaf being secured to said door, a hinge pin detachably fixed to each of said leaves, the adjacent ends of said pins being disposed between the adjacent edges of the leaves, and means for swivelly connecting said adjacent ends.

13. A hinge as in claim 12, said means comprising a socket detachably fixed to the adjacent end of one of said pins and loosely enclosing the adjacent end of the other pin.

14. A hinge as in claim 12, said means comprising a socket detachably keyed to one of said adjacent ends, said socket loosely containing said other adjacent end, said adjacent ends being provided with opposed concave recesses, and a ball bearing disposed therebetween for spacing said ends from each other.

15. A hinge comprising a substantially flat leaf, a second leaf having contiguous spaced portions provided with substantially flat, parallel outer sides, bolts fixed to said leaves and having head portions disposed between adjacent edges thereof, and a socket member connecting said heads for swivelly connecting the bolts and for mounting the hinge leaves in superposed relationship.

PAUL M. STEPHENS.
